WATCH

Henry A. Federman, New York, N.Y., assignor to The Pan American Barter Co., Inc., New York, N.Y., a corporation of New York

Original design application July 6, 1964, Ser. No. 80,713, now Patent No. 204,010, dated Mar. 8, 1966. Divided and this application Sept. 14, 1965, Ser. No. 87,246

Term of patent 14 years

(Cl. D42—8)

Fig. 1.

Fig. 2.

Fig. 3.

FIG. 1 is a top plan view of a watch showing my new design;

FIG. 2 is a side elevational view thereof; and

FIG. 3 is a bottom plan view thereof.

The essential features of my design are shown in full lines.

This application is a division of my co-pending application Serial No. D.80,713, which in turn is a continuation-in-part of my then co-pending application Serial No. D.75,852, filed July 17, 1963, but now abandoned.

I claim:

The ornamental design for a watch, as shown and described.
